UNITED STATES PATENT OFFICE.

CHARLES R. STEDMAN, OF CLEVELAND, OHIO.

GAS AND COAL BURNING FURNACE.

1,113,379.

Specification of Letters Patent. Patented Oct. 13, 1914.

Application filed February 14, 1907. Serial No. 357,250.

To all whom it may concern:

Be it known that I, CHARLES R. STEDMAN, a citizen of the United States, residing at Cleveland, in the county of Cuyahoga and State of Ohio, have invented certain new and useful Improvements in Gas and Coal Burning Furnaces, of which the following is a specification.

My invention relates to furnaces for burning gaseous or solid fuel either in combination or separately. Its object is primarily to provide convenient, inexpensive and effective means for accomplishing complete combustion of fuel within the fire spaces of a furnace, stove, steam boiler, water heater, or other fuel burning device to which it can be applied.

Further objects are to provide gas burning features which may be readily applied or removed from a fire space designed to burn solid fuel, to provide more permanent constructions, and to provide for the proper feeding and disposition of solid fuel in connection with the gas burning arrangement.

To these ends my invention consists in the features and combinations hereinafter described and claimed, embodiments and applications thereof being illustrated in the accompanying drawings in which—

Figure I is a sectional elevation showing the gas burning device as removably applied to an ordinary coal burning furnace. Fig. II is a sectional elevation of an installation of the gas burning device in a furnace adapted thereto. Fig. III is a longitudinal section of the gas burning retort. Fig. IV is an elevation of the fire end, and Fig. V is an elevation of the front or feeding end of Fig. III. Figs. VI and VII are sectional elevations of constructions and installations for large furnaces.

The reference letter *a* indicates a refractory retort lining, being a shell of fire-brick, fire-clay, or other fire resisting material, preferably, though not necessarily, of a substantially rectangular cross section and open at both ends. A perforated end piece, or brick, *b* of similar material, and of a contour corresponding to the outside of the lining *a* is fitted against the end of the latter, and said lining and end piece are held in a metallic shell or casing *c*, preferably of steel, having overlapping ears *d*, or other suitable means, for holding the end piece *b* in place against the lining *a*. The other end of the retort or more properly, intensifying cham-

ber, is closed by a cover *e*, being preferably of iron or steel, fitting the shell and held in place by a bent rod *g* sprung through apertures on opposite sides of the shell, as shown, so that it may also serve as a handle. The cover *e* may be removably attached to the shell in any suitable way however, and one or more openings *f* are made therethrough for the insertion of gaseous fuel pipes *h*. The aperture *f* is made larger than the diameter of its corresponding pipe *h*, so as to admit sufficient air to accomplish complete combustion within the retort *a*, and may if desired be arranged in spider form, as shown at *i*, Figs. III and V.

A mixer *j* for gas and air of the usual, or any suitable form is loosely fitted to the outer end of the pipe *h*, and held thereto by a set screw *k*. The mixer *j* is operatively connected and secured to a gas supply pipe *l* having a shut-off valve *m*. Thus, it will readily be seen that whether or not the intensifying chamber is fixedly secured to the fuel pipe *h*, it can be easily and quickly attached or detached from the mixer *j* by manipulation of the set screw *k*.

In Fig. I, the gas burning retort or intensifying chamber is shown removably installed in an ordinary coal burning furnace, or stove, in which *n* is the grate, *o* is the fire chamber, *p* is the smoke pipe, and *q* is the usual feeding door. In this case the outer end of the retort rests upon the feeding chute, but some additional support may be provided for the fire end, as shown at *r*. In other constructions the retort is supported upon the grate bars.

In Fig. II, the fire chamber *o* and grate *n* are long enough from front to rear to receive the retort or intensifying chamber and leave sufficient coal burning space *s* back of it. The front door *q* gives access to the retort, and a side door *t* opening into the space *s* is provided for feeding in coal, or other solid fuel.

In Fig. VI, the coal burning space *s* is in the forward portion of the fire chamber *o*, and adjacent to the front door *q* through which in this case the solid fuel is fed. An opening *u* is then made in the rear of the fire chamber for inserting the gas burning retort, and the plate *v* which closes the opening *u* may also take the place of the usual end plate *e* of the retort or intensifying chamber, as shown. Two gaseous fuel pipes *h* are shown in this case entering a single

retort, and it is obvious that a plurality of retorts may be placed in a single fire chamber if desired. Perforations may be made through the shell of the retort, as shown at 5 w , when the conditions of the installation require it.

In large furnaces, such, for example, as are employed for boilers of great capacity, the gas burning retort or intensifying chamber 10 may be built in of fire-brick, or similar material, forming one or more chambers x , as shown in Fig. VII. The rear wall of said chamber is perforated, as shown at y , so that the flaming gas enters the coal burning space 15 s , as in the other arrangements. The bottom and sides of the intensifying chamber are made tight, and the coal burning space s and grate n are placed between the wall y and a bridge wall z , beyond which is the usual combustion chamber 2 . A side door t similar to that shown in Fig. II, is employed in this construction for feeding in coal or other solid fuel. It is obvious that the fire and smoke passage p may be single or multiple, 20 that it may be carried forward and back through the body 3 of a boiler or heater, or arranged in any of the well known ways for providing heating surface and draft.

In the operation of the apparatus the mixture of combustible gas and air, having 30 been ignited, burns in the closed retort or intensifying chamber, generating therein a degree of heat so intense that the ordinarily non-combustible elements of the gas mixture 35 are consumed. The flames, therefore, which pass out through the perforations in the intensifying chamber are exceedingly hot, because all the elements of the gas mixture which are capable of the production of heat 40 through combustion have contributed to the evolution of heat, and substantially complete combustion of the mixture has occurred before the hot gases have approached or come in contact with any relatively cold surface. 45 And so if gaseous fuel alone is employed it is only necessary to provide sufficient heating surface about the fire chambers o and s , combustion chamber 2 , and the flue p , to absorb and transmit the heat already generated, in order to have effected a considerable economy in the consumption of gas. 50 But when coal, or other solid fuel, is burned in connection with gas, the economy of fuel becomes more apparent, for the reason that the intensely hot flames issuing from the perforations of the intensifying chamber give off 55 much of their heat to the burning coal, thus assisting the combustion of the latter. It is also evident that any smoke, soot and unburned products which rise from the solid fuel will enter the intense heat of the gas flames and be utterly consumed. Substantially complete combustion of both the gaseous and solid fuel is thus obtained, and with 60 sufficient heat absorbing surface adjacent to

the fire spaces and flues the escaping gases will be of a low temperature, and substantially free from smoke.

Therefore, I point out and distinctly claim as my invention:

1. In a furnace, the combination with a fire chamber and flue suitable for burning solid fuel, of an intensifying chamber located wholly within said fire chamber having perforations through its inner end communicating with said fire chamber, means for supplying said intensifying chamber with combustible gas, and means for supplying said intensifying chamber with sufficient air to sustain combustion within said chamber. 70

2. In a furnace, the combination with a fire chamber and flue suitable for burning solid fuel, of a self-contained intensifying chamber located wholly within and having perforations through its inner end communicating with said fire chamber, means for supplying said intensifying chamber with combustible gas, means for supplying sufficient air to sustain combustion within said 85 intensifying chamber, and means for removing said intensifying chamber from said fire chamber. 90

3. In a furnace, the combination with a fire chamber and flue suitable for burning solid fuel, of an intensifying chamber wholly within said fire chamber comprising a shell, a perforated end piece, a pipe projecting into said shell, means for supplying said pipe with combustible gas, and means for supplying sufficient air to sustain combustion within said intensifying chamber. 95

4. In a furnace, the combination with a fire chamber and flue suitable for burning solid fuel, of an intensifying chamber wholly within said fire chamber comprising a shell and a perforated end piece of fire resisting material, a closure for the other end of said shell, a pipe inserted through said closure 110 into said shell, means for supplying said pipe with combustible gas, and means for supplying sufficient air to sustain combustion within said intensifying chamber. 105

5. In combination with the fire chamber of a furnace for solid fuel, a self-contained gas burning intensifying chamber located therein comprising an inner shell and a perforated inner end piece of refractory material, an outer casing, a closure for the outer 120 end of said shell, a pipe inserted through said closure into said intensifying chamber, and means for supplying said pipe with gaseous fuel and air. 115

6. In combination with the fire chamber of a furnace for solid fuel, a self-contained gas burning intensifying chamber located therein comprising an inner shell and a perforated inner end piece of refractory material, an outer casing, a closure for the outer 125 130

end of said shell, a pipe inserted through said closure into said intensifying chamber, and a mixer for admitting gas and air removably connected with the outer end of 5 said pipe.

7. In combination with the fire chamber of a furnace for solid fuel, a self-contained gas burning intensifying chamber located therein comprising an inner shell and a per-
10 forated inner end piece of refractory material, an outer casing, a closure for the outer end of said intensifying chamber fitted within said outer casing and against the end

of said inner shell, removable means for retaining said closure in place, a pipe extending through said closure into said intensifying chamber, and means for supplying gaseous fuel and air to said pipe.

In testimony whereof I affix my signature in the presence of two subscribing wit-
nesses at Cleveland, Ohio, this 9th day of
February, 1907.

CHARLES R. STEDMAN.
